[57] CLAIM

The ornamental design for a golf club head, as shown and described.

DESCRIPTION

FIG. 1 is a plan view of a golf club head showing my new design;

FIG. 2 is a front elevational view thereof;

FIG. 3 is a left end elevational view thereof;

FIG. 4 is a right end elevational view thereof;

FIG. 5 is a rear elevational view thereof; and,

FIG. 6 is a bottom view thereof.

The broken line showing of a shaft fragment is for illustrative purposes only.
